SLIDING VANE PUMP

De Forest C. Inman, Clarkston, Mich.

Application December 15, 1947, Serial No. 791,815

1 Claim. (Cl. 103—135)

1

This invention relates to pumps of the sliding vane type.

An object of this invention is to provide a sliding vane pump embodying a rotor disposed eccentrically in the pumping chamber with pairs of piston blades loosely carried by the rotor and engageable with the wall of the chamber to provide for the suction of fluid at one side of the chamber and the pressure discharge of the fluid at the other side of the chamber.

Another object of this invention is to provide a sliding vane pump embodying parallel pairs of piston blades which are slidably carried by the rotor with each member of each pair independently movable relative to the other member of the same pair.

A further object of this invention is to provide a sliding vane pump embodying one or more pairs of piston blades slidably carried by the rotor, with the blades formed of fibrous or composition material so as to reduce the wear on the wall of the pumping chamber.

To the foregoing objects, and others which may hereinafter more fully appear, the invention consists of the novel construction, combination and arrangement of parts, as will be more specifically referred to and illustrated in the accompanying drawings, but it is to be understood that changes, variations, and modifications may be resorted to which fall within the scope of the invention as claimed.

In the drawing:

Figure 1 is a plan view, partly broken away and in section, of a sliding vane pump constructed according to an embodiment of this invention.

Figure 2 is a sectional view taken on the line 2—2 of Figure 1.

Figure 3 is a plan view of the rotor.

Figure 4 is a detailed side elevation of one pair of the piston blades.

Referring to the drawing, the numeral 10 designates generally a housing which is formed of a cylindrical wall 11 and the wall 12 formed integral with the wall 11. A removable end wall 13 is secured by fastening means 14 to the side wall or cylinder 11. The housing 10 also includes a base 15 which is adapted to be fixedly secured to a suitable support. The side wall or cylinder 11 has extending therefrom an intake 16 and an outlet nipple 17 disposed oppositely from and aligning with intake nipple 16. A rotor, generally designated as 18, is rotatably mounted in the cylinder 11 being eccentrically disposed so that the rotor 18 will be in substantially close contact with the lower side of the cylinder 11 as shown in Figure 2.

The rotor 18 includes a shaft 19 which rotatably extends through a bushing 20 carried by the end wall 11 and a gland 21 provides a seal for the shaft 19. The rotor 18 is formed with a pair of parallel slots 22 within which two pairs

of piston blades 23 are adapted to slidably engage. The blades 23 are of like construction and each includes, as shown in Figure 4, a pair of flat blade members 25 and 26 which are formed with an obliquely disposed inner edge 27. The outer ends of the blade members 25 and 26 are curved or rounded as indicated at 28 and 29, respectively, the curved portions 28 and 29 constituting the trailing portions of the blade members 25 and 26 by providing each blade structure from a pair of independently movable blade members 25 and 26, these blade members will centrifugally contact with the inner surface of the cylinder 11 upon rapid rotation of the rotor 18.

The blade members 25 and 26 are preferably formed of fibrous material such as pressed fiber or the like so that these blade members may, if desired, be impregnated with a lubricant and will not upon frictional engagement with the inner surface of the cylinder 11 unduly wear this inner surface.

In the use and operation of this pump the rotor 18 is rotated as shown in Figure 2 in counterclockwise direction so as to draw in fluid through the intake nipple 16 and as the blades near the outlet nipple 17 the fluid will be discharged through this nipple while at the same time the piston blades will slide endwise in the slots 22 of the rotor 18. The substantial point of contact between the rotor 18 and the cylinder 11 will provide a partition so that the fluid will be forcibly discharged through the outlet nipple 17.

I claim:

A sliding vane pump comprising a cylindrical housing, opposed intake and outlet members on said housing, an eccentric rotor rotatable in said housing, said rotor formed with a pair of spaced apart parallel slots extending transversely therethrough, a blade slidable in each of said slots, each of said blades including a pair of aligned blade sections, each of said blade sections having parallel side edges and an outer edge engageable with the inner wall of said housing, and an oblique inner edge between said parallel edges confronting a spaced oblique inner edge on the aligned blade section.
